(57) **CLAIM**

I claim the ornamental design for a disc container, as shown and described.

DESCRIPTION

FIG. 1 is a perspective view of a disc container, showing my new design;

FIG. 2 is a front view thereof;

FIG. 3 is a side view thereof;

FIG. 4 is a top view thereof;

FIG. 5 is a rear view thereof;

FIG. 6 is a bottom view thereof;

FIG. 7 is a perspective view thereof, in an opened condition;

FIG. 8 is a front view thereof;

FIG. 9 is a side view thereof;

FIG. 10 is a top view thereof;

FIG. 11 is a rear view thereof;

FIG. 12 is a bottom view thereof;

FIG. 13 is a modified embodiment of the design shown in FIGS. 1-12;

FIG. 14 is a side view thereof;

FIG. 15 is a front view thereof;

FIG. 16 is a top view thereof;

FIG. 17 is a rear view thereof;

FIG. 18 is a bottom view thereof;

FIG. 19 is a perspective view thereof, in an opened condition.

FIG. 20 is a side view thereof;

FIG. 21 is a front view thereof;

FIG. 22 is a top view thereof;

FIG. 23 is a rear view thereof; and,

FIG. 24 is a bottom view thereof.
